Primary Examiner — Jennifer Rivard*Assistant Examiner* — Alison M Ofstun(74) Attorney, Agent, or Firm — Hauptman Ham, LLP(57) CLAIM

The ornamental design for a cosmetic receptacle, as shown and described.

DESCRIPTION

FIG. 1 is a perspective view of a cosmetic receptacle showing the new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

In the drawings, the broken lines represent portions of the article that form no part of the claimed design.
